US0D1006231S

(12) **United States Design Patent** (10) Patent No.: **US D1,006,231 S**
(45) Date of Patent: ** Nov. 28, 2023

(54) **MULTI-PARAMETER DETECTOR FOR MEDICAL USE**

(71) Applicant: **BEIJING CHOICE ELECTRONIC TECHNOLOGY CO., LTD.**, Beijing (CN)

(72) Inventors: **Xiaolun Qian**, Beijing (CN); **Chuanlong Ma**, Beijing (CN); **Zesheng Xi**, Beijing (CN)

(73) Assignee: **BEIJING CHOICE ELECTRONIC TECHNOLOGY CO., LTD.**, Beijing (CN)

(**) Term: **15 Years**

(21) Appl. No.: **29/883,831**

(22) Filed: **Feb. 3, 2023**

Related U.S. Application Data

(62) Division of application No. 35/515,143, filed on Aug. 9, 2022 (U.S. filing date under 35 U.S.C. 384), and having an international filing date of Aug. 9, 2022, now Pat. No. Des. 982,759.

(57) **CLAIM**

We claim, the ornamental design for a multi-parameter detector for medical use, as shown and described.

DESCRIPTION

FIG. 1 is a perspective view of a multi-parameter detector for medical use, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

1 Claim, 7 Drawing Sheets
